GRILLEWORK FOR TREILLAGES, ROOM DIVIDERS OR THE LIKE

Barney Bright, Louisville, Ky., assignor to Julius Blum & Co., Inc., Carlstadt, N.J., a corporation of New York

Filed Oct. 21, 1965, Ser. No. 87,703

Term of patent 14 years

(Cl. D54—2)

FIG. 1

FIG. 2

FIG. 4

FIG. 1 is an elevational view of a grillework for trellages, room dividers or the like, it being understood that the grillework has this pattern throughout,

FIG. 2 is a side elevational view taken along line 2—2 of FIG. 1,

FIG. 3 is an enlarged transverse sectional view taken along line 3—3 of FIG. 1, and

FIG. 4 is an enlarged transverse sectional view taken along line 4—4 of FIG. 1.

I claim:

The ornamental design for grillework for trellages, room dividers or the like, substantially as shown and described.
